CLAIM

The ornamental design for a hose reel, as shown and described.

DESCRIPTION

FIG. 1 is a perspective view of a hose reel showing my new design;

FIG. 2 is a top plan view with the bottom plan view being a mirror image thereof;

FIG. 3 is a front elevational view with the rear elevational view being a mirror image thereof;

FIG. 4 is a right side elevational view thereof; and

FIG. 5 is a left side elevational view thereof.

The broken line showing of hose reel cart is for illustrative purposes only and forms no part of the claimed design.
